UNITED STATES PATENT OFFICE

168,589

REARVIEW MIRROR OR SIMILAR ARTICLE

Stanford Pavenick, South Orange, N. J.

Application March 22, 1952, Serial No. 19,006

Term of patent 14 years

(Cl. D14—6)

To all whom it may concern:

Be it known that I, Stanford Pavenick, a citizen of the United States, residing at South Orange, in the county of Essex and State of New Jersey, have invented a new, original, and ornamental Design for a Rearview Mirror or Similar Article, of which the following is a specification, reference being had to the accompanying drawing, forming part thereof.

In the drawing:

Fig. 1 is a front view of a rearview mirror or similar article showing my new design; and

Fig. 2 is a rear elevational view thereof;

Fig. 3 is a side elevational view taken from the right side of Fig. 1 and with the bracket member removed, and

Fig. 4 is a bottom plan view.

The dominant features of my design reside in the portions shown in full lines.

I claim:

The ornamental design for a rearview mirror or similar article, substantially as shown and described.

STANFORD PAVENICK.
